UNITED STATES PATENT OFFICE.

ERNST ROST, OF DRESDEN, GERMANY.

CUSHIONING DEVICE FOR VALVES.

SPECIFICATION forming part of Letters Patent No. 707,160, dated August 19, 1902.

Application filed September 16, 1901. Serial No. 75,516. (No model.)

To all whom it may concern:

Be it known that I, ERNST ROST, a subject of the German Emperor, and a resident of Dresden, Germany, have invented certain new and useful Improvements in Cushioning Devices for Avoiding the Shocks Caused by Valves Falling upon Their Seats, of which the following is a specification.

My invention relates to certain new and useful improvements in devices for avoiding the shocks caused by valves falling upon their seats, and broadly has for its object the provision of novel means whereby the valve when returning to its seat will be gradually and easily lowered without the attendance of the shock incident to a sudden release. This object is attained by mechanism hereinafter described, and fully set forth in the claims.

In the drawings, Figure 1 shows one form of a practical embodiment of my invention. Fig. 2 is a modification thereof. Fig. 3 is a section on line A B, Fig. 2. Fig. 4 is a section on line C D, Fig. 2. Fig. 5 shows another form in which my invention may be practiced. Fig. 6 is an elevation of the sleeve. Fig. 7 is a cross-section thereof. Fig. 8 is a section on a b, Fig. 5. Fig. 9 is a vertical sectional view of a still further modification. Fig. 10 is an elevation of the sleeve employed in said modification. Fig. 11 is a cross-section thereof. Fig. 12 is a section on X Y, Fig. 9. Fig. 13 is a still further modification, and Figs. 14 and 15 are detail views thereof.

In the drawings, Fig. 1, the lever b is connected at its one end to the valve-stem, which stem is actuated by the spring c. Releasing means a engage the other end of lever b. This lever is pivoted, as shown at h, and carries an arc-shaped projection f upon its lower face. A weight h is pivoted below lever b, as at i, and carries an engaging face g, adapted to contact with the projection f. Attention should be called to the slight movement part f will possess upon part g by reason of the peculiar shape of part f and its location with reference to i, effectually eliminating any sudden jar or shock upon the descent of the valve. A spring l bears upon the lower face of weight h for the purpose of creating friction, and thus retarding the motion of the weight. For the purpose of facilitating the return of the weight after the valve has been

raised a spring m is provided, which upon the lowering of the valve acts conjointly with the spring l. The backward movement of the weight may be varied at will by operation of stop-screw n, engaging part of weight h. It is desirable to reduce the shock and cause the same to be as perfectly elastic as is possible, and in order to carry out this desideratum I employ a stirrup p, (shown in Figs. 2, 3, and 4), which carries a stop-pin f', engaging part g' of weight h', which in turn is engaged by spring l' and m'; the construction in other particulars being the same as disclosed in Fig. 1.

In Fig. 5 I have shown a device in which a sleeve r is mounted upon the valve-stem. This sleeve carries projecting lugs s, which guide the same in grooves provided therefor in bridge t. At the upper end of the sleeve angularly-disposed lugs are secured which operate in weight v, as shown in Figs. 7 and 8, thereby rotating the weight. A spring x is mounted on the valve-stem, engaging nut w thereon and the upper end of the sleeve r for the purpose of assisting the gradual movement of the sleeve. A coil-spring z engages the weight v for returning the same to its position. A stop y is provided for limiting the rotative movement of the weight.

Fig. 9 illustrates a device broadly operative as the one just described. In this form, however, sleeve r' is provided with oppositely-disposed lugs s' u', which engage in contact-weights v' and v'', imparting a direct opposite rotary movement to the weights with relation to one another at the descent of the valve. The stem in this instance is also surrounded by a spring x', bearing against nut w' and sleeve r''.

Fig. 13 is an illustration of still another form of construction wherein the threaded valve-stem has a wedge-shaped part z' mounted thereon, which engages with a spring 1, having an upwardly-bent end, the spring being secured to the weight h'', imparting movement thereto by the downstroke of the valve causing the wedge to contact therewith. In this construction a stop-pin u'' adjusts the movement of the weight, as shown in Fig. 14, and spring 2, operating within a slot in the weight, tends to impart the necessary gradual movement equivalent to that given by springs l l' pre-

viously described in the modifications. In this form of construction the shaft to which the weight is connected is cut away, as shown at 12. The stop-pin *v*" thus engages the shaft 5 and limits its movement. By simply adjusting the height of the lower end of the stop-pin the shaft may rotate to a greater or less degree, as may be desired. As shown at 14, additional means are provided whereby the 10 rotation of the weight may be limited by adjusting the angularity of the weight with relation to the shaft.

Having thus fully described my invention, what I claim as new and useful, and desire to 15 secure by Letters Patent, is—

1. The combination with a valve and mechanism for moving the same, of a movable

weight and means on the valve-moving mechanism for moving the weight to check the movement of the valve. 20

2. The combination with the valve and mechanism for moving the same, of a movable weight and means on the valve-moving mechanism for moving the weight to check the movement of the valve, and means for returning the weight to its normal position in opening the valve. 25

In testimony whereof I have hereunto set my hand in presence of two witnesses.

ERNST ROST.
